UNITED STATES PATENT OFFICE.

JOHN COOK AND EMMIT P. HINKLE, OF SANTA RITA, NEW MEXICO.

LOCK SWITCH.

Application filed November 2, 1920, Serial No. 421,364. Renewed June 23, 1922. Serial No. 570,380.

To all whom it may concern:

Be it known that we, JOHN COOK and EMMIT P. HINKLE, citizens of the United States, both residing at Santa Rita, in the 5 county of Grant and State of New Mexico, have invented new and useful Improvements in Lock Switches, of which the following is a specification.

This invention relates to ignition switches 10 for automobiles and has for its object the provision of an ignition control switch provided with locking means whereby the switch may be locked in open position so that starting of the automobile by an un- 15 authorized person will be prevented, the device being furthermore provided with means whereby an attempt to unlock the switch with an improper key will result in the sounding of an audible alarm such as a bell or horn which will apprise the public 20 of the fact that an effort is being made to steal the automobile.

An important object is the provision of a device of this character including a slidable 25 plate carrying contact members adapted to be brought into engagement with stationary contact members interposed in the primary or secondary wires of the ignition system, the stationary contact members bridging 30 the contact members on the movable plate whereby the ignition system will be inoperative when the plate is in one position.

Another object is the provision of a device 35 of this character in which means is provided for automatically locking the movable plate in its circuit breaking position when it is moved, a proper key being required for releasing the lock before the movable plate can be moved to circuit closing position.

40 An additional object is the provision of a device of this character which will be comparatively simple and inexpensive in manufacture, highly efficient in use, positive in action, durable in service, and a general improvement in the art.

With the above and other objects and advantages in view the invention consists in the details of construction to be hereinafter more fully described and claimed, and illustrated in the accompanying drawings in which—

Figure 1 is an elevation of the device in position upon the dash of an automobile,

Figure 2 is a horizontal sectional view 55 through the dash showing the device in plan,

Figure 3 is a rear elevation,

Figure 4 is a front elevation of the back plate,

Figure 5 is an elevation of the intermediate fixed plate, showing the side engaged 60 by the movable plate,

Figure 6 is an elevation of the other side of the intermediate fixed plate,

Figure 7 is an elevation of the fixed plate 65 carrying the lock actuating means and showing the side engaging the parts shown in Figure 6,

Figure 8 is an elevation of the other side of the plate shown in Figure 7,

Figure 9 is an end elevation showing the 70 key-hole end,

Figure 10 is a longitudinal sectional view with the lock released,

Figure 11 is a longitudinal sectional view 75 with the lock engaged,

Figure 12 is a cross sectional view through the alarm contacts,

Figure 13 is a detail sectional view showing the means for holding the key spindle 80 in different positions,

Figure 14 is a fragmentary view showing the alarm circuit closed by use of an improper key, and

Figure 15 is a diagram of the circuits.

Referring more particularly to the drawings the letter A designates a portion of the dash of an automobile upon which our device, indicated at B, is secured by any suitable means.

In carrying out our invention we provide 90 a casing formed of top and bottom plates 20 between which are secured intermediate and front plates 21 and 22. The top and bottom plates 20 are grooved upon their confronting faces rearwardly of the intermediate plate 21, as shown at 23, and slidably 95 engaged within these grooves is the back plate 24.

This back plate is formed of insulating material and carries a plurality of spaced 100 pairs of contacts 25 which are interposed in either the primary or secondary circuit of

the ignition system of the automobile, wires C of the ignition system being severed and having their severed ends connected with the binding screws 26 holding the contacts 25. Upon its front face the plate 24 is provided with a recess 27 for the reception of a latch bolt, to be hereinafter described. Adjacent the recess 27 are contact screws 28 which extend through the plate 24 and which are adapted to be connected with a suitable source of current 29. Adjacent the screws 28 the plate 24 is provided with shallow grooves or recesses 30. Adjacent one side, the plate 24 is provided with a depression 31 and is also provided centrally with a groove 32.

Secured upon the intermediate plate 21 upon the face thereof and disposed against the movable plate 24 are transversely extending contacts 33 adapted to engage and bridge the pairs of contacts 25. These contacts 33 are held in place by suitable screws 34, the heads of which are disposed in the central groove 32 in the plate 24. This face 25 of the intermediate plate 21 is also provided with spaced parallel longitudinal grooves 35 receiving the heads of the binding screws 26 which hold the contacts 25 in place upon the plate 24. The provision of the various 30 grooves is to permit sliding movement of the plate 24, as will be clearly understood. Secured upon this face of the intermediate plate 21 is a leaf spring 36 having a bent free end 37 adapted to snap into the depression 31 in the plate 24 for holding the plate 24 at one limit of its movement. Secured upon the intermediate plate 21 are spaced longitudinally extending contacts 38 engaging the pair of screws 28 in the plate 40 24 and held in place on the plate 21 by screws 39 which have their heads disposed within the grooves 30 in the plate 24. At their free ends, these contacts 38 are bent laterally and extend through holes 40 in the 45 plate 21 and through holes 41 in the plate 22. The pairs of these contacts will be hereinafter described. The plate 21 is also provided with a rectangular hole 42 through which projects the latch bar to be herein- 50 after described and which is adapted to register with the bolt receiving recess 27 in the plate 24.

Upon its opposite side the plate 21 is provided with circular recesses 43 within which 55 are disposed the nuts for securing the contacts 33. Between the holes 40 is provided a longitudinal recess 44 which communicates with the rectangular holes 42 and within which is pivoted, as shown at 45, a latch member 46 having a lateral bolt end 47 adapted to be projected through the hole 42 and into the recess 27 for locking the plate 24 against movement. The edges of said bolt end 47 are inclined, as shown at 60 65 48. The outer edge, that is the edge oppo-

site to that from which the lateral end 47 extends, is V-shaped to provide inclined faces 49 and 50.

The front plate 22 is provided on its face confronting the plate 21, with a leaf-spring 51 which engages the inclined face 49 of the latch member for normally urging the lateral end 47 into engagement with the recess 27. The plate 22 is provided in one end with a key receiving slot 52 which communicates with a longitudinal slot 53 in the face of the plate 22. This longitudinal slot 53 has communicating therewith a laterally inclined branch 54 and is disposed in alignment with the longitudinal recess 44 in the plate 21, for a purpose to be described.

Secured within the plate 22 is a guide spindle 55 which extends longitudinally of the slot 53 and key-hole slot 52 and slidably and rotatably mounted upon this spindle 55 is a tumbler 56 including a disk-like portion 57 having diametrically opposite arms 58 formed thereon and further including a shank 59 having flattened sides 60 and 61. This shank 59 has formed upon the end thereof and extending toward the key-hole slot 52, a lug 62. A leaf spring 63 is secured within a recess 64 in the plate 22 and engages the flattened sides 60 and 61 of the tumbler shank for holding the tumbler in selected positions. A coil spring 65 surrounds the spindle 55 and abuts against the disk portion 57 of the tumbler for forcing the tumbler normally outwardly and the outward movement is limited by engagement of the disk portion 57 with the leaf spring 63. The plate 22 is provided with a hole 66 adjacent the holes 41 and the purpose of this hole is to accommodate one of the arms 58 of the tumbler when the same 105 is rotated and adjacent the hole 66 the plate 22 is recessed, as shown, to provide a shoulder 67 engageable by the other arm 58 for limiting movement of the tumbler member in one direction, the engagement of the first 110 mentioned arm 58 with the end of the hole 66 limiting its movement in the other direction. The bent ends of the contacts 38 which extend through the holes 40 and 41 in the plates 21 and 22 are disposed in alignment with the arms 58 on the tumbler member, for a purpose to be described.

Used in conjunction with my device is a key designated by the numeral 68 and comprising a tubular shank 69 slidably engageable upon the spindle 55 and provided with a slot 70 conformingly engageable upon the lug 62 on the tumbler. The key also includes an inclined bit 71.

The operation of the device is as follows: 125 With the parts constructed and assembled as above described and with the contacts 25 interposed in the ignition circuit and the contact screws 28 interposed in a circuit including the source of current 29 and a 130

suitable alarm, in the present instance shown as a bell, assuming that the automobile with which the device is associated is running, the plate 24 will be in circuit closing position, that is the contacts 25 carried thereby are in engagement with the transverse contacts 33 on the intermediate plate 21, these transverse contacts serving as bridges. At this time the bent end of the leaf spring 36 engages within the depression 31 in the plate 24 for holding the plate against accidental movement and the lateral end 47 of the latch member merely engages against the face of the plate 24. When the operator of the automobile wishes to stop the engine it is merely necessary that he push upon the projecting end of the plate 24 and slide it longitudinally whereupon the end 37 of the leaf spring 36 will ride out of the depression 31 and the recess 27 will register with the rectangular hole 42 in the plate 21 whereupon the lateral end 47 of the latch member, spring-pressed by the leaf-spring 51, will be projected into the recess 27, thus locking the plate 24 with the contacts 25 thereon out of engagement with the transverse contacts 33. It is of course apparent that upon initial movement of the plate 24 the ignition circuit will be broken and the engine stopped. The parts will remain in this locked position until use is made of the key 68.

In order to unlock the device to permit starting of the engine, it is necessary to insert the key 68 through the key-hole slot 52, whereupon the tubular shank 69 of the key will engage upon the spindle 55 and the slot 70 in the key shank will engage upon the lug 62 of the tumbler. The operator then rotates the key a quarter turn which results in the projection of the bit 71 into the inner end of the longitudinal slot 53. The operator then pulls the key outwardly whereupon the bit 71 will engage the inclined face 50 of the latch member and consequently depress the outer end of the latch member which will result in withdrawal of the lateral end 47 thereof from the recess 27. When this is done the plate 24 may be slid longitudinally to bring the contacts 25 thereon into engagement with the bridge contacts 33 and the circuit through the ignition system will be completed. When the plate 24 is thus slid the bent end 37 of the leaf spring 36 will snap into the depression 31. The operator may then push the key inwardly, rotate it to its original position and then withdraw it from the key-hole slot 52. The parts will remain in this position until the plate 24 is slid to break the circuit.

In the event of an unauthorized person's trying to unlock the device with an improper key the action is as follows:

If the key is used which locks the slot 70 in its shank, the shank will engage the end

of the lug 62 on the tumbler whereupon forcing of the key inwardly to permit turning thereof will result in longitudinal movement of the tumbler 56 upon the spindle 55, the spring 65 being compressed. This inward movement of the tumbler will result in engagement of the arms 58 with the ends of the contacts 33 which will close the circuit through the alarm device which being a horn or bell, will apprise the public of the fact that an attempt is being made to steal the automobile. If the unauthorized person should have a key having its shank provided with the proper slot 70 but having a bit with the improper inclination the key could not be rotated for unlocking the device, even though the alarm might not be sounded for the reason that the key bit must have a certain inclination in order to pass through the branch slot 54 and the latch member could therefore not be manipulated to effect unlocking of the device. It is therefore seen that ample protection is provided for preventing operation of the device by anyone other than the one possessing the exact key necessary.

If desired, a flange may be provided at the key end of the device in order that the device may be positioned through the dash of an automobile and be disposed beneath the hood so as to be entirely out of the way and also invisible except for the key receiving end. Another possibility is that if it is desired to move the automobile equipped with our device, in case of an emergency such as a fire or the like, we may arrange a wire connected with the alarm and with one spark plug, the connection to be made by the insertion of a small key or nail or the like, into the key receiving opening so as to close the circuit, the automobile then being capable of being run upon one cylinder only with the alarm sounding continuously.

From the foregoing description and a study of the drawings it will be apparent that we have thus provided an ignition switch which is readily operated by the proper person for switching on or off the ignition circuit of an automobile engine and which is provided with efficient and positive means for the protection of the automobile against theft.

While we have shown and described the preferred embodiment of our invention, it is of course to be understood that we reserve the right to make such changes in the form, construction, and arrangement of parts as will not depart from the spirit of the invention or the scope of the subjoined claims.

Having thus described our invention, we claim:

1. A device of the character described comprising a casing, a plate movable within said casing, a plurality of spaced contacts carried on the outer face of said plate

and interposed in the ignition wire of an internal combustion engine, a fixed plate forming part of said casing, a plurality of contacts on said fixed plate adapted to be engaged by and bridge said first named contacts, means for limiting the sliding movement of said movable plate, said movable plate being provided with a recess, a latch member pivoted within said fixed plate and having an angular end portion normally engaging within said recess for holding said movable plate against movement, a front plate forming a part of said casing and provided in one end with a key-hole slot, and a key disposable within said slot and movable to release said latch member from engagement within said recess.

2. A device of the character described comprising a casing, a slidable plate mounted therein and carrying contacts interposed in the ignition circuit of an automobile engine, fixed contacts within said casing and engageable by said first named contacts for closing the circuit through said ignition system when said movable plate is in one position, means for locking said movable plate in circuit breaking position, key operated means for releasing said movable plate to permit movement thereof, and key operated means for sounding an alarm in the event of the use of a false key.

3. A device of the character described comprising a casing, a plate movable within said casing and carrying contacts connected in the ignition system of an automobile engine, fixed contacts within said casing engageable by said first named contacts for making a circuit, means for limiting movement of said slidable plate, said plate being provided with a keeper recess, said casing further including a fixed plate provided with a hole adapted to register with said recess and being further provided with a longitudinal recess communicating with said hole, a latch member pivoted within said last named recess and having an angular end adapted to be projected into said recess, the opposite edge of said latch member being V-shaped whereby to provide inclined faces, said casing further including a front plate, a leaf spring carried by said front plate and engaging one of the inclined faces of said latch member for forcing said latch member into said keeper recess, said top plate being provided in one end with a slot and with a key-hole slot entering thereinto, a guide spindle within said last named slot in combination with a key engageable upon said spindle and rotatable whereby to bring its bit into engagement with the other inclined face of said latch member whereupon outward movement of the key will result in retraction of said latch member from said keeper recess.

4. A device of the character described

comprising a casing including a top plate, a fixed intermediate plate and a slidable back plate, a plurality of contacts carried by said back plate and interposed in the ignition circuit of an internal combustion engine, a plurality of contacts carried by said fixed intermediate plate and engageable by said first named contacts for bridging the latter, a pair of contact screws extending through said movable plate and interposed in a circuit including a source of current, a pair of contact members secured upon said intermediate fixed plate and always engaging said contact screws, key releasable automatically engaging locking means for holding said movable plate against movement in circuit breaking position, and means operated by the use of a false key for bridging said pair of contacts whereby to close said circuit.

5. A device of the character described comprising a casing including a top plate, a fixed intermediate plate and a slidable back plate, a plurality of contacts carried by said back plate and interposed in the ignition circuit of an internal combustion engine, a plurality of contacts carried by said fixed intermediate plate and engageable by said first named contacts for bridging the latter, a pair of contact screws extending through said movable plate and interposed in a circuit including a source of current, a pair of contact members secured upon said intermediate fixed plate and always engaging said contact screws, key releasable automatically engaging locking means for holding said movable plate against movement in circuit breaking position, and means operated by the use of a false key for bridging said pair of contacts whereby to close said circuit, said means comprising a spring pressed member mounted within the top plate of the casing, said top plate being provided with holes receiving extensions on said pair of contacts, and said spring-pressed member being engageable by the end of the shank of a false key whereby said member will be moved into engagement with said extensions.

6. A device of the character described comprising a casing, a movable plate forming a part of said casing, a plurality of contacts carried by said movable plate and interposed in an ignition circuit, other contacts within said casing engageable by said first named contacts whereby to bridge the same when said plate is in one position, a latch member for holding said movable plate normally in circuit breaking position, a spindle within said casing, said casing being provided with a key-hole slot adjacent said spindle, a tumbler slidable and rotatable upon said spindle and carrying arms, a pair of contacts within said casing adjacent said tumbler interposed in a circuit in-

cluding a source of current, and a lug on said tumbler in combination with a key having a tubular shank engageable upon said spindle and having a bit engageable with said latch member whereby to effect release of the same, said tubular shank having a slot engageable upon said lug, insertion of a false key unprovided with such a slot causing movement of said tumbler with said arms engaging said pair of contacts for closing said circuit.

In testimony whereof we affix our signatures.

JOHN COOK.
EMMIT P. HINKLE.
